TROWEL AND WEEDE

Norman E. Brooke, Washington, D. C.

Application July 13, 1945, Serial No. 604,837

4 Claims. (Cl. 294—50.6)

1

This invention relates generally to the class of gardening implements or tools and pertains particularly to an improved combination trowel and weeder.

A primary object of the present invention is to provide a trowel or trowel and weed removing tool, of a novel construction whereby an extreme rigidity is obtained throughout the length of the implement without having to use metal of excessively heavy weight, such a novel construction giving the desired rigidity at the part of the implement where the body or blade portion is joined with the tang by which the blade is coupled with a handle.

A principal source of annoyance associated with the use of trowels and similar tools which are pressed from sheet metal, is the extreme weakness to be found at the point of connection between the handle and the blade of the tool, as the result of which, when the tool is used in unusually firm ground and it becomes necessary to impose a heavy strain on the handle, the metal fails at the point of connection between the handle and the blade and the tool becomes useless.

In the present invention the above stated annoyances are avoided by the novel construction of the implement wherein there is formed along the longitudinal center of the implement blade and the tang, and throughout the length of both, a stiffening rib which is unbroken throughout its length and which gives such extreme rigidity to the implement, particularly in the narrow portion where the tang joins the blade, that the application of strains greatly in excess of those ever applied to a hand implement of this character, will not cause a breakdown of the structure and bending of the connection between the blade and tang.

Still another object of the invention is to provide in an implement of the character stated, a novel means of connecting the tang portion of the implement with a wooden handle whereby a firm and secure joint is established between the two parts by the use of only a single fastening element.

Still another object of the invention is to provide in an implement of the character stated, a novel means of closing a sleeve-like tang around a handle body so that a firm gripping action is obtained between the tang portion and the handle, such gripping action being increased as the securing element is tightened in place.

Other objects and advantages of the present invention will become apparent as the description of the same proceeds and the invention will be

2

best understood from a consideration of the following detailed description taken in connection with the accompanying drawing forming a part of the specification, with the understanding, however, that minor changes and modifications may be made in the invention so long as such changes or modifications mark no material departure from the salient features of the invention as expressed in the appended claims.

10 In the drawings: Figure 1 is a view in bottom plan of a trowel and weeder constructed in accordance with one embodiment of the present invention.

Figure 2 is a view in side elevation of the same. Figure 3 is a view in top plan.

Figure 4 is a sectional view taken transversely of the trowel on the line 4—4 of Figure 2. Figure 5 is a detail view in which the securing bolt is cut off below the head, showing the construction of the wings, the section being substantially on the line 5—5 of Figure 6.

Figure 6 is a sectional view taken on the line 6—6 of Figure 2. Figure 7 is a view in top plan of a trowel and weeder constructed in accordance with another embodiment of the invention.

Figure 8 is a view in side elevation of the same. Figure 9 is a sectional view taken substantially on the line 9—9 of Figure 8.

Referring now more particularly to the drawing, the numeral 10 generally designates the body or blade portion forming the trowel proper. This blade is of substantial length as shown and it is formed or pressed from a body of sheet metal of desired weight and has extending from one end, the sleeve-like tang which is generally designated 11 and which forms a part of the sheet metal body of the blade.

40 The tang 11 upon the back or underside 12, is of substantial length and there extends from the longitudinal side edges, the inwardly curved wing portions 13 which are designed to be brought into edge opposed relation as shown in Figure 5 to form a complete collar in which an end of a handle body 14 is positioned.

The opposing edge portions of the wings 13 are relatively short as indicated at 15 and each has the semi-circular recess 16 formed therein. 50 These recesses combine to form an opening or space for a securing bolt 17 which passes through the handle 14 and through the back 12 of the tang to receive the securing nut 18.

The bolt 17 has a T head 19 which extends 55 across the opposing edges 15 and is of slightly

arcuate form to substantially conform to the curvature of the handle and the collar portion of the tang. At its ends the T head 19 of the bolt has the sharply downturned tips 20 which bear against the surfaces of the wings and function to draw the wing ends in together as the head is drawn tight against the surfaces of the wings.

While the tang portion 11 is in the form of a collar to encircle the handle, it is not completely circular because of the fact that it is pressed longitudinally of the underside 12 to form the central longitudinal ridge 21. Likewise, the blade portion 10, while it is of generally arcuate cross section as shown in Figure 4, is not a complete section of a circle but is pressed along its longitudinal center to form the ridge 22. Thus the portions of the blade at each side of the ridge 22 are curved and each may form a portion of a circle but they come together in such a manner that the cross sectional design of the blade is more in the form of a pointed arch. As is readily seen upon reference to Figure 1, the ridge portion 21 of the tang and the ridge portion 22 of the blade are in fact one and the same since the ridge is complete and unbroken throughout the length of the blade and of the tang, passing around the heel portion 23 where the tang joins the blade and extends at an oblique angle to the length thereof. By means of this angulation of the tang, the handle 14 when attached to the tang, extends at the required angle to the length of the blade to facilitate the proper use of the trowel.

At the tip or working end of the trowel blade the material of the blade is extended at each side of the longitudinal center to form the weeding tongue 24. The forward end of this tongue is provided with the relatively deep V-shaped recess or notch 25 whereby there is formed the pair of points 26 and the side edges of the recess or notch 25 are sharpened as indicated at 27 so that deeply rooted weeds may be cut off below the surface of the ground to be conveniently removed.

To further facilitate the use of the weeder tip 24, the points 26 are slightly turned upwardly as illustrated.

Figures 7 to 9 inclusive illustrate a modified construction of the combined trowel and weeder, the modification being made in the rear end portion of the structure where it is attached to the handle.

In this modified form the body of the trowel is generally designated 27 and, as shown, is of the same form or design as the body 19. However, at the inner or rear end of the body 27 the integral tang extension 28, while it has the longitudinal pressed central ridge 29 which forms a continuation of the ridge 30 of the body, is not provided with side wings such as the wings 13, but is substantially straight along its longitudinal edges 31 and is substantially semi-circular in cross section as shown in Figure 9.

The handle 32 lies within the channel-like tang 28 and is secured thereto by the bolt 33 which passes through a suitable bore formed transversely through the handle 32 and which has the head 34 of the arcuate form, the underside of which is formed on a smaller arc than the curved face of the handle which it straddles so that opposite end edges of the head will bite into the body of the handle 32, as shown in Figure 9, when the nut 35 is drawn up tightly against the underside of the tang 28 through which the bolt passes as shown.

In this modified construction it will be noted

that the tang 28 is bent upwardly slightly from the line of the ridge 30 of the body portion so that the handle 32 will be maintained at a suitable angle to the underside of the trowel body to facilitate the use of the implement.

From the foregoing it will be readily apparent that the implement of the present invention is so designed that it will have a maximum of strength, particularly at the point where this type of implement is usually found extremely weak, that is, across the bent or heel portion 23 where the tang angles off from the blade. By continuing the rib 22 through the length of the blade, the heel and the tang, an extreme degree of rigidity is given to the entire tool which makes it possible for the tool to withstand extremely heavy or great strains.

I claim:

1. A gardening implement of the character described, comprising a one-piece body formed of sheet metal and consisting of a relatively long blade portion of substantially arcuate cross section, a portion of the blade section at one end being extended to form a substantially arcuate tang portion, said tang portion being at a slightly oblique angle to the length of the blade portion and having a portion of each longitudinal edge extended to form inwardly curving wings whereby to form a handle encircling collar, the part of the sheet metal body at the joined blade and tang portions being slightly rounded to form a heel, the blade and tang portions of the body and the intermediate heel portion being pressed outwardly from the inner side to form a continuous stiffening ridge, the free longitudinal edges of the wing portions being disposed in opposed relation, each of said edges having a recess formed therein, and a bolt adapted to pass between said edges and lie in said recesses and to extend through a handle and through the tang portion to receive a securing nut, said bolt having an arcuate T head adapted to engage the outer surfaces of the wings at opposite sides of the recessed edges.

2. A gardening implement of the character described, comprising a one-piece body formed of sheet metal and consisting of a relatively long blade portion of substantially arcuate cross section, a portion of the blade section at one end being extended to form a substantially arcuate tang portion, said tang portion being at a slightly oblique angle to the length of the blade portion and having a portion of each longitudinal edge extended to form inwardly curving wings whereby to form a handle encircling collar, the part of the sheet metal body at the joined blade and tang portions being slightly rounded to form a heel, the blade and tang portions of the body and the intermediate heel portion being pressed outwardly from the inner side to form a continuous stiffening ridge, the free longitudinal edges of the wing portions being disposed in opposed relation, each of said edges having a recess formed therein, and a bolt adapted to pass between said edges and lie in said recesses and to extend through a handle and through the tang portion to receive a securing nut, said bolt having an arcuate T head adapted to engage the outer surfaces of the wings at opposite sides of the recessed edges, and the end portions of said T head being sharply turned inwardly to form pressure tips designed to draw the wings together around the end portion of a handle extending therebetween.

3. A combination trowel and weeder, comprising a relatively long trowel blade, means at one

end of the blade for securing a handle thereto, a portion of the blade body at the opposite end being of a width materially less than the blade body and extending longitudinally from the central portion of the blade, the portion of less width having straight parallel sides, said longitudinally extending reduced portion having a substantially V-shaped recess cut therein the edges of the recess merging with said sides and forming spaced earth penetrating points, the edges of the V-shaped portion being sharpened, the trowel blade and the extended portion thereof being of substantially arcuate cross section, the said points being curved slightly away from the underside of the blade.

4. A trowel, comprising a relatively long body of substantially arcuate cross section having convergently arranged forward and side edge portions, each of said side edge portions converging with a short straight edge portion, said short straight edge portions being parallel one with the other and with the longitudinal center of the trowel body and a relatively deep V-shaped recess cut in the forward end of the trowel body between the short straight edge portions, the

edges of the recess intersecting the adjacent straight side edge portions to form penetrating points, the said edges of the recess being sharpened and said points being curved upwardly slightly away from the underside of the trowel.
